ELECTRICAL CONTROL SYSTEMS AND CONTROL
DEVICES THEREFOR

James Courtney, Donaghadee, Northern Ireland

Application April 17, 1953, Serial No. 349,521

Claims priority, application Great Britain April 18, 1952

3 Claims. (Cl. 307—112)

This invention relates to electrical control systems and control devices therefor.

According to the present invention I provide an electrical control system including at least two alternative control points, each control point comprising electro-mechanical means in circuit with the control system, switch means adapted, when closed, to connect the control system and the electro-mechanical means with a source of electrical power, and, for the switch means, lock means operable by the electro-mechanical means, when energised, the arrangement being such that, operation of the switch means at one control point to effect closure of same prevents locking of that switch means and, at each other control point, effects locking of the switch means in the open position.

Further, according to the present invention I provide a control device for use in a control system having at least two alternative control points comprising electro-mechanical means adapted to be connected in circuit with the control system, switch means adapted, when closed, to connect the control system and electro-mechanical device with a source of electrical power, and, for the switch, lock means operable by the electro-mechanical means, when energised, the arrangement being such that, when a control device as aforesaid is provided at each control point, operation of one switch means to effect closure of same prevents locking of that switch and, at each other control point, effects locking of the switch means in the open position.

An embodiment of the invention will now be described, by way of example with reference to the accompanying diagrammatic drawing, in which:

Fig. 1 is a plan view of the electrical lay-out at one control point, and

Fig. 2 is a fragmentary plan view showing details of the lock means.

Referring to Fig. 1 of the drawing, the system at each control point consists of a solenoid coil 1 which is connected in circuit through leads 2, 3 with two main conductors 4, 5 from which a number of relay devices (not shown) may be energised. Also, at each control point there is provided two electrical batteries 6, 7 and a drum type switch 8. The switch handle (not shown) has three positions. In the mid-position, the circuit is open and in either of the other two positions, one on each side of the mid-position, the circuit is closed, current passing from one or other of the batteries 6, 7 to the solenoid coil 1 and to the leads 2, 3. This current, of course, passes along the conductors 4, 5 to energise the solenoid coil at each other control point in the system. The contacts for the switch 8 are indicated generally at 9 and 10 for the battery 6 and at 11 and 12 for the battery 7. The handle of the switch 8 is removable only in either of the closed positions of the switch.

The lock means will now be described with reference to Fig. 2 of the drawing. The solenoid coil 1 is located below the switch drum, and its plunger 13 is loosely piv-

2

otally connected intermediate the ends of an arm 14. The arm 14 is pivotally connected at one end by a pin 15 to the base of the casing of the switch 8, and adjacent its other end has a recess or slot 16, and the spindle 17 of the switch 8 has a pin 19 engageable by the slot 16. The arm 14 is urged to the position shown in full lines against a fixed stop 20 by a spring 21, and is movable to the position shown in chain-dotted lines in which the slot 16 engages the pin 19, as shown, so that the switch is locked in its open position. The positions of the pin 19, when the switch 8 is in either of its closed positions are indicated at 19A and 19B.

In use, the system is energised from one battery at one control point. When the handle of the switch 8 at this control point is moved to a closed position, say to select battery 6, the contacts 9, 10 are closed, the solenoid coil 1 is energised and current passes along the conductors 4, 5 and energises the solenoid coils at each other control point. For convenience, the control point at which the switch has been closed will now be referred to as the first control point, and the other point or points as the second control point.

When, as aforesaid, the switch 8 at the first control point is closed to select battery 6, the pin 19 is rotated on the spindle 17 to the position 19A (Fig. 2). In this position, it will be seen that, though the arm 14 swings inwards under the action of the plunger 13 when the coil 1 is energised, the slot 16 cannot engage the pin 19 and this switch is not locked. As aforesaid, however, the coil 1 at the second control point is also energised, the switch being open and the pin 19 in the position shown in full lines. Thus, the plunger 13 swings the arm 14 inwards so that the slot 16 engages the pin 19, and locks the switch at the second control point in its open position.

When the switch 8 at the first control point is opened, the coils 1 at each point are de-energised, and the arms 14 are swung and held clear of the pin 14 by the springs 21.

It will thus be seen that, at any one time, the system can be controlled only from one control point, and that when the switch at one control point is closed it is not possible for the switch at any other control point to be operated, so that either accidental or unauthorized operation of the additional controls is obviated.

The invention is especially applicable to the feed for the various controls for a train formed by a number of rail cars, and in this case there is one control point in each powered rail car. At each control point there is a number of different controls for which only one operating handle is provided, the present control system being one of these and that which is operated first of all, and for this reason the handle can be removed from the switch in the present invention only when the switch is closed.

The control system is, of course, equally applicable to rail cars having control points at each end and to any number of cars single or dual controlled forming a train. Also, in some cases, there may only be one battery at each control point, in which a switch having only two positions is used.

Modifications may be made without departing from the scope of the invention and it is to be clearly understood that the invention is not restricted to use in rail cars.

I claim:

1. An electrical control system including at least two alternative control points, each control point comprising manually operable switch means for the control system, lock means for the switch means, and electro-mechanical means for operating the lock means, the switch means being in circuit with the electro-mechanical means, with the control circuit and with a source of electrical power,

and all the electro-mechanical means being connected in parallel with the control system, whereby, when the switch means at any one selected control point is closed, the electro-mechanical means at all the control points are energised and operate the lock means which lock the unselected switch means in the open position.

2. An electrical control system as claimed in claim 1, in which locking of the selected switch means in the closed position is prevented by virtue of the fact that the lock means comprises two interengageable elements, one of which, when the switch means is closed, is moved to a position in which it cannot be engaged by the other element.

3. An electrical control system including at least two alternative control points, each control point comprising a manually operable rotary switch, lock means for the switch, an electro-mechanical device for operating the lock means, and an electric battery, the switch being in circuit with the electro-mechanical device, with the control circuit and with the battery, and all the electro-mechani-

cal devices being connected in parallel with the control system so that, when the switch at any one selected control point is closed, the electro-mechanical devices at all the control points are energised, the lock means at each 5 control point comprising two locking elements, the first of which is carried by the spindle of the switch and in the open position of the switch lies in a position in which it may be engaged by the second element when actuated by the electro-mechanical device and which, when the selected 10 switch is closed, is rotated with the spindle of the switch to a position in which it cannot be engaged by said second element of the lock means so that when the selected switch is closed it is not locked while all the other switches in the system are locked in the open 15 position.
